United States Patent Office

Des. 216,873
Patented Mar. 17, 1970

216,873

FOOD SERVICE BUILDING

Robert H. Spain, Fort Lauderdale, and Sidney R. Wilkinson, Brodertown, Fla., assignors to Chris McGuire, Inc., Fort Lauderdale, Fla., a corporation of Florida

Filed June 24, 1969, Ser. No. 17,854

Term of patent 14 years

Int. Cl. D25—04

U.S. Cl. D13—1

FIG. 2

FIG. 3

Des. 216,873

PAGE 3

FIG. 5

FIG. 6

FIG. 1 is a perspective view of the food service building showing our new design;

FIG. 2 is a front elevational view of the building shown in FIG. 1;

FIG. 3 is a side elevational view of said building;

FIG. 4 is an elevational view of the other side of said building;

FIG. 5 is a back elevational view of said building; and FIG. 6 is a top plan view of said building.

We claim:

The ornamental design for a food service building, as shown and described.
